(57) **CLAIM**

The ornamental design for a noise monitoring headset, as shown and described.

DESCRIPTION

FIG. 1 is a front perspective view of a noise monitoring headset in accordance with the new design;

FIG. 2 is a front view of the noise monitoring headset in accordance with the new design;

FIG. 3 is a rear view of the noise monitoring headset in accordance with the new design;

FIG. 4 is a right side view of the noise monitoring headset in accordance with the new design;

FIG. 5 is a left side view of the noise monitoring headset in accordance with the new design;

FIG. 6 is a top view of the noise monitoring headset in accordance with the new design;

FIG. 7 is a bottom view of the noise monitoring headset in accordance with the new design; and,

FIG. 8 is a rear perspective view of a noise monitoring headset in accordance with the new design.

The broken lines shown in the drawings are only provided to illustrate the environment of the design, and form no part of the claimed design.

1 Claim, 7 Drawing Sheets
